Primary Examiner — George D. Kirschbaum*Assistant Examiner* — Darcey E Heflin(74) *Attorney, Agent, or Firm* — Manuel de la Cerra(57) **CLAIM**

The ornamental design for a beverage container lid, as shown and described.

DESCRIPTION

FIG. 1 is a top perspective view of a beverage container lid. FIG. 2 is a bottom perspective view thereof.

FIG. 3 is a top perspective view of a second embodiment made from transparent material.

FIG. 4 is a bottom perspective view thereof made from transparent material.

FIG. 5 is a top perspective view of FIG. 1, wherein the lid is attached to a beverage container and a straw.

FIG. 6 is a top view thereof.

FIG. 7 is a bottom view thereof.

FIG. 8 is a front view thereof.

FIG. 9 is a rear view thereof.

FIG. 10 is a left-side view thereof; and,

FIG. 11 is a right-side view thereof.

The broken lines in FIG. 5 illustrate environmental structures and form no part of the claimed design.
